BLADE TESTING APPARATUS

Ernest Paul Floyd, Fitchburg, Mass., assignor to
Simonds Saw and Steel Company, Fitchburg,
Mass., a corporation of Massachusetts

Application June 7, 1935, Serial No. 25,421

5 Claims. (Cl. 73—51)

This invention relates to apparatus for determining the cutting ability of a blade or blades, and not only permits a quantitative determination of the keenness of a blade, but also permits the determination of rate and extent of the deterioration thereof, as well as the comparison of the sharpness or the deterioration thereof of two or more blades.

To permit these desirable results, a sheet of material of known characteristics, such for example as paper of standardized character, may be pressed against a given portion of the edge of the blade with a determined pressure and then relative movement may be effected between the sheet and the blade in the direction of extent of the cutting edge, this movement being continued until the sheet of known characteristics has been severed. Thereupon the extent of the movement is measured to afford an indication of the cutting ability of the blade.

In order to permit the convenient testing of a blade in this manner, I have devised a machine which includes a blade support arranged to hold a blade with its cutting edge uppermost and a weight guide disposed above and in parallel relation to the cutting edge of the blade mounted upon the support. A weight is associated with the guide so that normally it rests not on the guide but on the cutting edge of the blade or on a sheet of material, such as paper, disposed over the cutting edge of the blade. The weight may be in the form of a block or supporting element shaped conveniently to slide along the guide and provided with means to receive various additional weight elements of known mass. Thus the total weight of the supporting element and the element supported thereby may be known. The element itself provides a portion having a known dimension of constant size, which rests on the blade or on a sheet of paper engaging the cutting edge of the blade.

Thus the paper may be forced against a known extent of the blade under a determined pressure. The sheet may then be grasped and pulled manually until it is severed, whereupon the weight rests upon the cutting edge of the blade, although the sheet may continue to move. The weight guide may be provided with a graduated scale so that the length of the path of the weight is readily determined.

Obviously when a sharp blade is employed, a relatively short movement of the paper and weight is required in order to result in the severing of the paper, while when the blade is relatively dull, a much longer movement is required. Thus the scale permits convenient observation of the length of the path of movement of the weight, and accordingly permits convenient ascertainment of a quantitative indication of the cutting ability of the blade. If this operation is repeated

a plurality of times, the length of the path of the weight will gradually increase, thus permitting a plurality of readings to be taken so that a curve can be drawn to indicate the deterioration in cutting ability of the particular blade. It is obvious that several blades may be compared in this manner to permit convenient determination of their relative cutting abilities or the relative deteriorations thereof.

In the accompanying drawing,

10

Fig. 1 is a plan view of apparatus constructed in accordance with this invention;

Fig. 2 is a front elevation of the same, the weight being shown in a dotted line position which it may occupy at the end of its path; and 15

Fig. 3 is a side elevation of the apparatus.

Referring to the accompanying drawing, which is illustrative of the invention, the apparatus may comprise a blade support in the form of a pair of blocks 1, which are provided with aligned 20 slots 10 to receive a cutting blade 2 which is to be tested. Each slot may be dimensioned so that the blade fits tightly therein to preclude relative movement of the blade and its support, or, if desired, thumbscrews 11 may be arranged in 25 order to clamp the blade tightly in its support. Extending upwardly from each of the blocks 1 are a pair of spaced uprights 3, which may be arranged at opposite sides of the slot 10 but in non-symmetrical relation thereto, so that the 30 beveled cutting edge 12 of the blade may have its cutting portion lying midway between the uprights 3. Secured upon the upper surfaces of the uprights 3 are a pair of guide rails 5 which form a weight guide. The weight 20 may include 35 a lower supporting portion 6 of T-shaped cross section, the depending portion of the member 6 being loosely received between the guide rails 5, and the outstanding flanges thereof being disposed over the rails 5 but spaced therefrom. 40

A stud 8 may extend upwardly from the member 6, and a weight element 7 may be provided with a central hole so that it may be disposed in concentric relation to the stud 8 and rest upon the upper surface of the member 6. Thus the 45 weight includes the supporting member 6, the stud 8 and the weight element 7. A plurality of elements 7 having different weights may be provided so that these members may be interchangeably disposed on the supporting member 6 as 50 required.

As shown particularly in Fig. 1, the rails 5 may be provided with graduated scales, the zero point of each scale being arranged so that the right-hand edge of the weight member 6 (as viewed in 55 Fig. 1) may register with the zero graduation when the weight is at the left end of its path. When a device of this character is to be used in testing the cutting ability of a blade, a sheet of material of known characteristics, such as a 60

sheet of standardized paper stock which has substantially uniform characteristics, may be disposed on the cutting edge of the blade between the same and the lower portion of the support 6. 5 Thus, as is particularly evident from an inspection of Fig. 3, the entire weight of the assembly 20, including the support 6, the stud 8 and the element 7, rests upon the portion of the paper which is being pressed against the cutting edge 10 of the blade.

Since the member 6 has a determined width or extent along the cutting edge of the blade, a determined portion of the paper is being pressed against the cutting edge. When the parts are 15 in this position, the edge of the paper 4 is grasped and moved slowly toward the right, as viewed in Fig. 2, carrying the weight 20 until the paper is severed through, whereupon the weight will rest upon the cutting edge of the blade and the paper 20 may readily be removed from the device. Thereupon the reading on the scale which registers with the right-hand edge of the member 6, is observed to afford an indication of length of the 25 path of the weight and of the cutting ability of the blade during this particular test.

A similar operation may be performed a plurality of times employing a piece or pieces of paper of the same characteristics. Under these conditions the extent of the path of the weight 30 will gradually increase as the cutting ability of the blade decreases. Thus a plurality of readings taken following tests in this manner will afford a good indication of the tendency of the cutting ability of the particular blade to deteriorate, it of course being evident that the lengths of the paths of relative movement are inversely proportioned 35 to the cutting ability of the blade.

It is evident that a plurality of blades may be in turn disposed in the machine and each blade 40 tested once to afford a quantitative comparison of the cutting abilities of the respective blades, or that the several blades may be each tested a number of times so that a determination of the relative durabilities of their cutting edges may 45 be afforded.

When a blade is so dull that the standardized piece of paper stock can not be cut through during a single movement of the weight, the movement may be repeated and the added lengths of 50 the two movements will afford an approximate quantitative indication of the cutting ability of the blade at the particular time. However, under such conditions it is preferable to substitute a heavier weight element 7, thus increasing the 55 total weight of the weight assembly 20.

It is evident that the present invention affords a simple yet accurate means for determining the cutting abilities of blades either individually or in comparison tests, and either to afford an indication of the initial sharpness of the blade or blades or the durability of their cutting edge or edges thereof.

It should be understood that the present disclosure is for the purpose of illustration only and 65 that this invention includes all modifications and equivalents which fall within the scope of the appended claims.

I claim:

1. Apparatus for determining the cutting abil-

ity of a blade, comprising a framework including a supporting portion, a weight-guiding portion, and a scale portion parallel to the weight-guiding portion, and a weight slidable relative to the guiding portion but arranged so that it may rest 5 on the edge of a blade mounted on the supporting portion, whereby a sheet with the weight resting thereon may be drawn along the edge of the blade until the sheet is severed and the weight rests upon the blade edge, whereupon the length 10 of the path of the weight may be observed.

2. Apparatus for determining the cutting ability of a blade, comprising a base having a blade supporting portion to hold a blade with its cutting edge uppermost, a weight guide extending parallel to said blade supporting portion, a scale associated with said guide, and a weight movable along said guide and arranged so that it may rest upon a sheet engaging the blade edge or the edge itself, whereby a sheet with the weight resting 20 thereon may be drawn along the edge until the sheet is severed and the weight rests upon the edge, whereupon the extent of the movement of the weight may be determined by observing its position relative to the scale. 25

3. Apparatus for determining the cutting ability of a blade, comprising a base arranged to receive and support a blade with its cutting edge disposed uppermost, a weight guide including parallel guide rails, weight means having a portion 30 depending between the guide rails to rest upon the cutting edge or on a sheet engaging said edge, and scale means associated with one of said rails, whereby a sheet with the weight resting thereon may be drawn along the edge until the 35 sheet is severed and the weight rests upon the edge, whereupon the extent of the movement of the weight may be determined by observing its position relative to the scale means. 40

4. Apparatus for determining the cutting ability of a blade, comprising a base arranged to receive and support a blade with its cutting edge disposed uppermost, a weight guide including parallel guide rails, a weight support having a portion depending between the guide rails to rest 45 upon the cutting edge or on a sheet engaging said edge, and a weight removably mounted on said support, and scale means associated with one of said rails, whereby a sheet with the weight resting thereon may be drawn along the edge 50 until the sheet is severed and the weight rests upon the edge, whereupon the extent of the movement of the weight may be determined by observing its position relative to the scale means. 55

5. Apparatus for determining the cutting ability of a blade comprising a base having a blade supporting portion to hold a blade with its cutting edge uppermost, a weight guide arranged above said blade supporting portion and a weight movable along said guide and arranged so that 60 it may rest upon a sheet engaging the blade edge or the edge itself, whereby a sheet with the weight resting thereon may be drawn along the edge until the sheet is severed and the weight rests upon the edge whereupon the extent of the movement of the weight may be observed to afford an 65 indication of the cutting ability of the blade.

ERNEST PAUL FLOYD.
